UNITED STATES PATENT OFFICE.

WILLIAM E. KERNS, OF VINTON, IOWA.

STARTING APPARATUS.

Application filed March 23, 1925. Serial No. 17,786.

To all whom it may concern:

Be it known that I, WILLIAM E. KERNS, a citizen of the United States, residing at Vinton, in the county of Benton and State 5 of Iowa, have invented certain new and useful Improvements in Starting Apparatus, of which the following is a specification.

This invention relates to improvements in starting apparatus adapted for use in connection with internal combustion engines 10 and the like.

An important object of the invention is to provide a cranking apparatus wherein the crank is readily removable.

15 A further object of the invention is the provision of apparatus of the above character which may be readily mounted in association with the conventional types of internal combustion engines and greatly facilitate the starting thereof.

20 A still further object of the invention is the provision of a cranking apparatus of the above character which is positive and comparatively safe in operation yet simple and durable of construction.

25 Other objects and advantages of this invention will become apparent as the description progresses.

In the accompanying drawing, forming a 30 part of this specification and in which like numerals are employed to designate corresponding parts throughout the same:

35 Figure 1 is a side elevation of my improved apparatus shown in the inoperative position with the starting crank withdrawn,

Figure 2 is a similar view showing the device in operative position and the crank inserted,

40 Figure 3 is an end elevation of the device,

Figure 4 is a transverse sectional view taken on the line 4—4 of Figure 2, and

Figure 5 is a perspective view of a portion of the crank member.

45 In the drawings, wherein for the purpose of illustration is shown the preferred embodiment of my invention, the numeral 10 generally indicates the body or casing of my improved apparatus which is of metallic 50 construction and oblong in cross section, the upper and lower edges being rounded as clearly illustrated in Figures 3 and 4. The upper portion of the body is provided with square bore 11 extending longitudinally 55 through the body. The lower portion of the body or casing 10 is provided with a some-

what larger circular bore 12 also extending longitudinally therethrough and communicating with the exterior of the body by means of an angular oil groove 13. 60

Slidably fitted in the upper bore 11 is a square guide shaft 14 substantially longer than the body and provided upon one extremity with an offset extension 15 extending in parallel alignment with the shaft 14 65 upon a somewhat lower plane. Formed on the forward extremity of the extension 15 is a substantially semi-circular bracket 16 carrying on each end horizontally extending ears 17 provided with suitable apertures 18 70 to permit fastening of the device in association with an internal combustion engine frame.

Rotatably mounted in the lower bore 12 is a cylindrical sleeve 19 having formed on the rear extremity thereof a ratchet 20. The rear edge of the ratchet is provided with a plurality of arcuate pin engaging teeth 21 engageable with the crank pin for rotation of the same. Extending through the greater 75 portion of the sleeve 19 and communicating with the forward extremity thereof is a substantially square bore 22 adapted to receive therein a portion of the crank member to be hereinafter more fully described. 80

The sleeve is retained against longitudinal movement by means of a collar 23 rigidly secured to the forward extension of the sleeve by set screws 24. 85

Detachably engageable with the rotatable 90 sleeve member 19 is an angular crank 25 the body of which is of the usual construction while the upper engageable extension 26 is provided adjacent the extremity with a square shank 27, the extreme end of which is beveled to permit convenient engagement with the bore 22 formed in the sleeve. The edges of the outer extremity of the bore 22 are also beveled as at 29 for the reception of the crank. The opposite extremity of the crank 25 is provided with the usual handle member, not shown, whereby the crank may be readily rotated for starting the motor. 95

It is customary in devices of this character to provide means for normally forcing the ratchet out of engagement with the crank shaft in order to prevent violent rotation of the starting crank with the shaft and the danger of injury by such action. I accomplish this by the provision of a coiled 100 compression spring 30 positioned about the rear extension of the shaft 14, restraining 105

this spring against displacement by a cotter pin 31 positioned through a suitable bore formed adjacent the end of the shaft. The spring 30 exerts pressure against the rear portion of the body or casing 10 and normally forces same tightly against the vertical connection bar 32 connecting the guide shaft 14 with the offset extension 15, the tension of this spring being so regulated as to readily move the casing upon the guide shaft but permit compression thereof by the operator without extraordinary effort.

The device may be readily used upon the common forms of automobiles, tractors and similar vehicles but is especially adaptable for use upon the well known Ford type of automobile. When mounting the apparatus upon the Ford car the bracket 16 replaces the usual crank case bearing cap and is secured in position by two bolts. The casing then snugly fits in the forward extension of the crank case and is ready for use.

In using my improved apparatus, the crank 25 may be carried in any convenient place upon the automobile and when it is necessary to crank the motor for starting purposes may be readily inserted by engaging the shank 27 formed in the sleeve 19. The operator then pushes forward on the crank and causes the body or casing 10 to slide upon the guide shaft 14 until the ratchet 20 engages the transversely positioned pin mounted on the forward end of the crank shaft. The crank handle is then rotated until the motor has been started after which the axial pressure exerted upon the crank is relaxed and the casing permitted to move to the forward portion of the guide shaft 14 and the crank removed. Thus it is seen that the crank may be very readily and positively connected with the rotatable sleeve for efficiently turning over the motor.

It is to be understood that the form of my invention herewith shown and described is to be taken as the preferred example of the same, and that various changes as to the shape, size and arrangement of parts may be resorted to without departing from the spirit of the invention, or the scope of the subjoined claims.

Having thus described my invention, I claim:

1. In a device of the class described, a casing, guide means adapted to permit longitudinal movement of the casing, means for normally forcing the casing toward one end of the said guide means, a rotatable member mounted in the said casing, crank shaft engaging means carried by the said rotatable member, and means for positively connecting the crank with the said rotatable member.

2. In a device of the class described, a body, a guide shaft adapted to permit lon-

gitudinal movement of the said body, a sleeve rotatably mounted in the said body, and means for connecting a crank with the said sleeve.

3. In a device of the class described, a body, a guide shaft extending through the upper portion of the body adapted to permit movement of the body thereon, means for normally forcing the body to the forward portion of the guide shaft, a sleeve rotatably mounted in the lower portion of the body, a crank pin ratchet carried by the said sleeve, a crank adapted to rotate the said sleeve and means for positively connecting the said crank with the sleeve.

4. In a device of the class described, a substantially oblong casing member, a guide shaft through the upper portion of the casing, means for normally forcing the casing upon the forward portion of the said guide shaft, a sleeve rotatably mounted in the lower portion of the casing, a crank pin ratchet carried by the rear extension of the said sleeve, a crank, and means for positively connecting the said crank with the said rotatable sleeve.

5. In a device of the class described, a casing having a longitudinal bore formed in the upper portion and a similar bore formed in the lower portion, a guide shaft slidably mounted in the upper bore, means formed on one end of the guide shaft for connection with an internal combustion engine, spring means carried by the opposite end of the guide shaft for normally forcing the casing upon the forward portion thereof, a sleeve rotatably mounted in the lower bore, a ratchet carried by the forward end of the said sleeve, means for preventing displacement of the said sleeve, a crank having a rectangular extension, and means for engaging the said crank with the rotatable sleeve.

6. In a device of the class described, a casing of substantially oblong cross section having a longitudinal bore formed in the upper portion and a similar bore formed in the lower portion thereof, a guide shaft extending through the upper bore, means formed on the guide shaft for securing the same in connection with an internal combustion engine, a coiled spring mounted on the opposite end of the guide shaft adapted to normally force the casing on the forward portion thereof, a rotatable sleeve mounted in the lower bore of the casing, a ratchet carried by the said sleeve, a collar secured to the opposite end of the said sleeve for preventing displacement thereof, a crank shaft having a rectangular extension, and means whereby the said extension may positively engage the said rotatable sleeve.

7. A device of the class described including a casing having a square bore formed in the upper portion and a circular bore in

the lower portion thereof, a shaft extending through the upper bore adapted to guide the casing, an offset extension formed on the forward extremity of the guide shaft, a bracket means formed on the ends of the said extensions, a spring carried by the rear extremity of the guide shaft, a sleeve rotatably mounted in the lower bore of the casing, a ratchet carried by the said 10 sleeve, the forward portion of the said sleeve being provided with an internal opening, a crank having a rectangular extension, and means whereby the said extension may engage the opening formed in the said rotatable sleeve.

8. A device of the class described in-

cluding a casing, a guide shaft adapted to support the said casing, means for connecting the said guide shaft upon an internal combustion engine, means for normally forcing the casing toward the forward portion of the guide shaft, a rotatable sleeve mounted in the lower portion of the casing provided with a rectangular bore, a ratchet carried by the said sleeve, means for preventing displacement of the said sleeve, a crank shaft having a rectangular extension, and means whereby the said crank shaft extension may engage the bore of the rotatable sleeve for operation of the same. 20 25 30

In testimony whereof I affix my signature.

WILLIAM E. KERNS.
